RECEIVING CHAMBER FOR PNEUMATIC CLEANING APPARATUS

Robert P. Sweeny, Atlanta, Ga.

Application April 15, 1940, Serial No. 329,840

13 Claims. (Cl. 182—67)

The present invention relates to improvements in air inductor cleaners of the type used in cotton mills. This application constitutes a continuation-in-part of my co-pending application S. N. 295,514, filed September 18, 1939, and entitled "Pneumatic cleaning apparatus."

The cleaner has primary utility in stripping lint and foreign matter from carding machinery.

One object is to provide a cleaner which will effectively separate dust from lint.

A second objective is to avoid twisting and knotting of the lint, and to avoid rolling it into balls.

In cotton mills cleaning apparatus of this type is also used in cleaning floors and machines, as well as for stripping cards. Lint and other fibers picked up by the cleaners are generally reclaimed and utilized. If the air stream in which the lint and dust is carried is overturbulent, the fibers become twisted, knotted and co-mingled with dust so that extensive reclaiming processes are necessary. Accordingly, the reduction in operations necessary for reclaiming the fibers after they have been deposited in the cleaner is an object.

One of the primary objects of this invention is to provide a receiving chamber in which the lint is not only deposited free from knotting, but also in which dust is automatically separated from the lint.

A specific object is to provide baffle structure not only positively to guide the dust and lint in their respective movements, but also to facilitate in separating any grouped lint fibers and for liberating dust therefrom.

Still again, it is intended to reduce the cost in machine parts, repair, and cost of operation by utilizing relatively low pressure air, which may be economically supplied in large volume.

A further objective is to provide positive, predictable control of the matter picked up by the cleaner.

The structure which provides these and other advantages will be clear from the following specification and drawing, in which:

Fig. 1 is a side elevation, partially broken away, of the assembly;

Fig. 2 is a side elevation of the lower, inclined shelf with baffles; and

Fig. 3 is a plan view of the lower inclined shelf and baffles shown in Fig. 2.

Referring particularly to Fig. 1, the numeral 10 indicates the suction intake pipe which is connectable at 12 to a pipe leading to the cleaning nozzle. The induction chamber 14 is adapted

to be connected to a source of compressed air (not shown) at the threaded end 18. At the outlet end 19, the induction chamber is connected by the sectional expansion duct 20, comprising three sections 76, 88 and 96, respectively, to the receiver 22. Receiver 22 is closed at its upper end by a top 2, and has a cloth bag 23 at the lower end. As seen best in Fig. 1, the expansion duct enters the receiver near the top and spirals downwardly therein.

In the interior of the receiver 22, the coiled portion of the expansion duct ends at mouth 28 from which the lint and dust-laden air is discharged.

15 Immediately above the mouth 28 of expansion duct 20 the upper, inclined shelf 30 is secured so that it extends around the inner wall of the receiver and ends at the lower side of mouth 28 of the expansion duct.

20 As shown particularly in Fig. 1 and Fig. 2, there is a lower inclined shelf 32 extending substantially parallel to upper inclined shelf 30, the lower inclined shelf starting at the lower side of mouth 28 of the expansion duct and extending downwardly and around the inner wall of the receiver 22.

25 With reference to Figs. 2 and 3, the lower inclined shelf 32 has a non-radial baffle 34 mounted, as shown at 36, on the top surface of the shelf. Shelf 32 ends with a downwardly projecting lip 38 and has on its under side the baffle 40 secured at 41 and a second baffle 42 secured at 43. It should be noted that the baffles 40 and 42 extend substantially radially with respect

30 to the center of receiver 22. Immediately beneath mouth 28 of expansion duct 20 there is mounted substantially radially with respect to the center of the receiver 22 the large baffle 44 which has at its top a curved seat as shown by the reference numeral 46 for accommodating the lower end of the expansion duct. The large baffle has, at its lower corners, the forwardly turned deflector 48 and the rearwardly turned deflector 50. The large baffle 44 preferably extends down

35 40 45 below the bottom of receiver 22, and into the bag as shown in Figs. 1 and 2.

The operation of the general assembly is as follows:

When the compressed air supply is connected at 18 to the induction chamber, the cleaning nozzle (which may be of the type shown in either of my earlier patents, Nos. 1,426,428 and 1,559,804, although it is obvious that other types of cleaning nozzles may be used) is passed over the elements to be cleaned of lint and/or dust. The

lint and dust are drawn through the suction intake pipe 10, passed through the sectional expansion duct 20 and are blown into the receiver from the mouth 28.

The upper inclined shelf 30 and the lower inclined shelf 32 guide the air which carries dust and lint downwardly as it passes around the inside walls of the receiver 22. When the air carrying the dust and lint strikes the upper non-radial baffle 34, the circumferential velocity of the moving matter is broken and some of the air and lint is deflected towards the center of the receiver, thereby enabling the air further to expand and lose velocity. The remaining compressed air and lint continues around, being guided downwardly by upper and lower shelves 30 and 32, respectively, until striking large baffle 44 which deflects the greater portion of the air and lint inwardly and downwardly into a cloth bag 23 which is attached at the bottom of the receiver. Baffle 44 also serves to help diffuse the compressed air and helps prevent the air from swirling around in the cloth bag 23.

The large baffle 44 includes deflectors 48 and 50 which tend to direct portions of the air containing dust, which is lighter than the lint, towards the wall of the bag 23, and radial baffles 40 and 42, and lip 38 finally stop such swirling motion.

The effect of the assembly is that the heavier particles, which are comprised chiefly of lint, strike the non-radial baffle 34 and are dropped inwardly and downwardly to the bottom of the bag. The swirling motion of the air which carries dust and lint is not immediately "killed," but is allowed to pass downwardly around the sides of the receiver until striking the large baffle which causes the remaining lint to drop to the bottom of the bag. Dust, however, being lighter, is blown by the air which is still under some compression to the sides of the cloth bag 23 to which it adheres and from which it may be collected separately from the lint which is reposed in the bag.

It should be noted that the baffles, particularly 34 and 44, not only direct the lint and dust as described above, but they also break up any matted fibers, thereby separating them from each other and from dust. Since the swirling motion of the air is not immediately "killed" by the baffles, it is serviceable to transport the dust particles which are relatively light in weight to the sides of bag 23.

Having herein described some embodiments of my invention, I wish it to be known that I do not intend to limit myself thereby, except within the scope of the appended claims.

I claim:

1. In a separating device, a receiving chamber having a substantially closed upper end portion and a bag forming the lower portion of said receiving chamber, said bag having a substantially closed lower end portion, an expansion duct disposed in said upper end portion, said duct being provided with inlet and outlet openings disposed on alternate ends thereof, upper shelf means extending inwardly from the inner wall of said chamber and spiraling downwardly from a point adjacent the upper side of said outlet opening of said duct to a point intermediate said upper and lower end portions of said receiving chamber, lower shelf means extending inwardly from the inner wall of said chamber and spaced below said upper shelf means, said lower shelf means spiraling downwardly from a point

adjacent the lower side of said outlet opening to a point intermediate said upper and lower end portions of said receiving chamber, and baffle means on said lower shelf means, said baffle means extending substantially transverse to said lower shelf means.

5 2. In a separating device as defined in claim 1, said upper and lower shelf means being spaced from and parallel to each other.

3. In a separating device as defined in claim 1, said expansion duct having a spiral configuration.

4. In a separating device as defined in claim 1, said expansion duct spiraling downwardly and progressively increasing in cross-sectional area from the upper end to the lower end thereof, and said outlet opening being disposed on the lower end thereof.

5. In a separating device as defined in claim 1, the lower end portion of said upper shelf and the upper end portion of said lower shelf being adjacent to each other and held in a substantially abutting relationship.

20 6. In a separating device, a receiving chamber having a substantially closed upper end portion and a bag forming the lower portion of said receiving chamber, said bag having a substantially closed lower end portion, an inlet pipe disposed in said upper end portion, said inlet pipe having an exhaust opening at one end thereof, an upper shelf extending inwardly from the inner wall of said chamber and spiraling downwardly from a point adjacent the upper side of said exhaust opening of said inlet pipe to a point intermediate said upper and lower end portions of said receiving chamber, a lower shelf extending inwardly from said inner wall of said chamber and spaced below said upper shelf, said lower shelf spiraling downwardly from a point adjacent the lower side of said exhaust opening to a point intermediate said upper and lower end portions of said receiving chamber, and baffle means on said lower shelf, said baffle means extending substantially transverse to said lower shelf.

40 7. In a separating device as claimed in claim 6, the outer edges of said shelves engaging, respectively, against the inner side of the wall of said receiving chamber.

8. In a separating device as claimed in claim 6, the said upper shelf forming substantially one convolution around the inside of said chamber from the upper side of said exhaust opening substantially to a point below the lower side of said exhaust opening, the lower end of said upper shelf extending circumferentially beyond the lower end of said lower shelf.

50 9. In a cleaning apparatus, a substantially cylindrical receiving chamber having top and bottom closure members, an expansion duct having inlet and outlet openings, said outlet opening being disposed intermediate said top and bottom closure members, an upper shelf extending inwardly from the inner wall of said chamber and spiraling downwardly from a point adjacent the upper side of said outlet opening, a lower shelf extending inwardly from said inner wall of said chamber and spaced below said upper shelf, said lower shelf spiraling downwardly toward said bottom closure member, said lower shelf being provided with an upstanding baffle mounted on the upper side thereof.

70 10. In a cleaning apparatus as claimed in claim 9, the lower end of said upper shelf extending around the inner side of the wall of said chamber substantially to below the lower side of said outlet

opening, and a transverse baffle mounted beneath said lower shelf substantially at the upper end thereof.

11. In a cleaning apparatus as claimed in claim 9, the upper shelf extending around the inner side of the wall of said chamber to a point substantially below the lower side of said outlet opening, a transverse baffle mounted beneath said lower shelf near the upper end thereof, the inner lower corner of the last-mentioned baffle being turned rearwardly with respect to the direction of air flow, the outer lower corner thereof being turned forwardly with respect to the direction of the air flow.

12. In a cleaning apparatus as claimed in claim 9, said upstanding baffle extending substantially across the upper surface of said lower shelf at an angle to the radius of said chamber, the lower end of the upper shelf extending circumferentially beyond the lower end of the lower shelf substantially to below the lower side of said outlet opening, a transverse baffle mounted at a point below the lower side of said outlet opening, and having in the top edge thereof a curved seat for embracing said expansion duct at a point adjacent said outlet opening, the outer edge of said transverse baffle being engaged against the inner side of the wall of said chamber and extending downwardly to a point substantially below the

bottom edge of said chamber, the lower inner corner of said transverse baffle being turned rearwardly with respect to the direction of air flow, the lower outer corner being turned forwardly with respect to the direction of air flow, and a second transverse baffle mounted substantially below the central portion of said lower shelf.

13. In a cleaning apparatus as claimed in claim 9, the upstanding baffle extending substantially across the upper surface of said lower shelf at an angle to the radius of said chamber, the lower end of the upper shelf extending circumferentially beyond the lower end of the lower shelf and substantially to a point below the lower side of said outlet opening, a transverse baffle mounted below the lower side of said outlet opening and having in the top edge thereof a curved seat for embracing said expansion duct at a point adjacent said outlet opening, the outer edge of said transverse baffle being engaged against the inner side of the wall of said chamber, the lower inner corner of said transverse baffle being turned rearwardly with respect to the direction of air flow, the lower outer corner being turned forwardly with respect to the direction of said air flow, and a plurality of transverse baffles mounted on the under side of said lower shelf.

ROBERT P. SWEENEY.
